UNITED STATES PATENT OFFICE

LOUIS J. VIEHMANN, OF DOUGLASTON MANOR, NEW YORK, ASSIGNOR TO TEEPEE-WHITNEY CORPORATION, OF LONG ISLAND CITY, NEW YORK, A CORPORATION OF NEW YORK

TABLE

Application filed March 31, 1930. Serial No. 440,395.

My invention relates to improvements in tables intended for kitchen and/or dining room purposes, and the same has for its object to provide a simple, compact and attractive table which may be readily enlarged by leaf or extension members which are normally wholly concealed within or below the table top.

Further, said invention has for its object to provide an extension table of simple construction in which the extension or leaf members are normally wholly housed and concealed within and by the table top, and which may be readily moved from their retracted or inoperative position to their extended or operative position in a straight line or horizontal plane parallel to the table top in its normal position.

Further, said invention has for its object to provide an extension table in which the extension or individual leaf members arranged at opposite sides of the table when withdrawn or adjusted to operative position will have their inner edges in close engagement with the respective edges of the main member or table top, and their upper surfaces in a horizontal plane coinciding exactly with that of the upper surface of the main member or table top.

Further, said invention has for its object to provide an extension table in which a plurality of extension or leaf members are normally housed and concealed within and by the main member or table top, and in which the main member or table top is so constructed that the same is capable of a limited vertical movement and tilting movements transversely in order to permit of the adjustment of said extension or leaf members to operative and inoperative positions, and vice versa by merely slightly raising the edges of said main member or table top.

Further, said invention has for its object to provide an extension table in which a plurality of extension or leaf members are normally housed by and within the main member or table top, and in which the latter is yieldingly or movably secured along its central, longitudinal axis to the supporting frame so as to permit the raising of its longitudinal

edges whereby to withdraw first the extension or leaf member at one side of the table, and then the one at the other side of the table.

Further, said invention has for its object to provide an extension table in which the hollow metal top, is braced or reinforced and protected against undue injury by extension or leaf members and their respective supports disposed within and below said hollow top.

Further, said invention has for its object to provide an extension table in which the same supporting and guiding means is common to and serves to guide and support the extension or leaf members at opposite sides of the table.

Other objects will in part be obvious and in part be pointed out hereinafter.

To the attainment of the aforesaid objects and ends, my invention consists in the novel details of construction, and in the combination, connection and arrangement of parts hereinafter more fully described and then pointed out in the claims.

In the accompanying drawings—

Figure 1 is a front view illustrating one form of table constructed according to and embodying my said invention;

Fig. 2 is an under side view of the table, the legs being shown as broken away;

Fig. 3 is a cross-section taken at about the plane of the lines 3—3 in Fig. 1 and showing the main table top down flat and housing both leaves;

Fig. 4 is an end view showing the top tilted and the leaf on the left-hand side partly extended, the leaf on the right hand side being in its retracted and housed position;

Fig. 5 is a cross-section showing the leaf at the left fully extended, the edge of the main top dropped behind it, and the leaf at the right hand side half way out;

Fig. 6 is an end view showing both leaves fully extended, the main top in position behind them, the entire upper surfaces of the leaves and main table portion being in the same horizontal plane, and

Fig. 7 is a detail in projection of a portion of the corner of the table looking from below and showing a modified or alternative means for securing the main table top to the frame.

so that it may readily be tilted transversely towards each of its longitudinal edges.

The table herein illustrated has an oblong supporting frame comprising a pair of longitudinal side members 10, a pair of end members 11, and legs 14^a all of which are secured together by means of clamp plates 12 and screws 13 entering the tops of said legs 14^a. This is a conventional form of construction, and does not form part of my invention aside from the fact that the frame members cooperate with elements which do enter into the invention, and the frame members are modified in certain respects to accommodate my construction.

The main member or table top 14 is preferably formed of metal which may or may not be provided with an enamel coating according to the intended uses to which the table is to be put. In the illustration this main table top is of substantially the same form as the frame, but is preferably somewhat larger. The top is shown having a dependent flange 15 which is preferably in-turned at its lower edge 16, and within the flange and its in-turned edge is disposed a wooden frame 17 comprising longitudinal side members 17^a, end members 17^b, and a central longitudinal member 18 which is secured at its opposite ends to the inner sides of the end members 17^b, and serves to divide the under side of the top within the frame member 17 into two longitudinal recesses 18^a, to receive the separate extension members or leaves. The frame 17, as a whole, also serves to stiffen or reinforce the metal top, and protect the same against injury which might ordinarily occur as a result of pressure or sudden impact against the upper side thereof. The bar 18 normally rests upon the end frame members 11 at about their central portion. Each of the longitudinal side frame members 10 is shown provided in its upper edge of its ends with a recess 19. A pair of guide rails 20 are located crosswise of the table in said recesses 19, and are secured to the frame members 10. For the purpose of steadyng the main table top 14 and guiding it in its tilting movement, the rail 18 carries a pair of depending pins 21 which are loosely received in holes 22 in the guide rails 20. The holes 22, however, are sufficiently close to prevent undue movement of the table top upon the supporting frame. For limiting the lifting or the upward movement of the table top the pins 21 are shown provided with heads 23 which are larger than the openings 22 and located in position to permit a pre-determined upward movement of the table top and the tilting thereof transversely towards each of its longitudinal edges.

The dimensions of the flange 15, rails 20, and the bar 18 are preferably such that the lower surface 24 of the in-turned portion 16 of the flange 15 occupies a plane above the

plane 25 occupied by the tops of the legs 14^a and the frame members 10 and 11, see Figs. 1 and 6. Each of the guide rails 20 is provided at each side with a tongue 26. The said tongues engage and cooperate with grooves 27 formed in slide rails 28 and 29 secured to the leaves 30, 31, respectively. Stops 32 and 33 are shown secured to the under sides of the slide rails 28 and 29, respectively, for the purpose of limiting the outward or withdrawing movement of the leaves.

The slide rails 28 and 29 are cut away inwardly of the leaves which they carry so as to present surfaces 34 at a proper distance below the upper surfaces of the leaves to accommodate the depth of the edge of the main table top when the same drops into position behind the leaf when the latter is fully extended.

Preferably the leaves are of such proportions that they will fully occupy the recesses 18^a in the under side of the main table top formed between the bar 18 and the inner edges of the longitudinal frame members 17^a or the flange 15. Suitable finger recesses 35 are shown formed in the under side of the front edges of the extension leaves.

The outer edges of the extension leaves are formed with curved lines so as to produce an ornamental appearance of the table when they are extended, which differs from the outline of the main table top when the leaves are retracted below and within the same.

From the foregoing it will be apparent when the leaves 30 and 31 are fully retracted and in the folded position of Figs. 1 and 3, that they are, not only as to their upward surfaces but as to their outer edges, completely concealed from view and protected from soiling or injury from the culinary operations which may be carried on upon the main table top. It will also be seen that the bar 18, the guide pins 21, the guide rails 20 and slide rails 28 and 29 afford stable and adequate support for the table top both in the retracted or inoperative position or in a position with one leaf or both leaves extended to operative position.

Assuming that the leaves are in their normal or retracted positions shown in Figs. 1, 2 and 3, and it is desired to withdraw and extend them, it merely becomes necessary to raise one longitudinal edge of the table with one hand as, for example, the left hand side at Fig. 3, and grasping with the other hand the forward edge of the leaf 31 at the recess 35 until its front edge appears below the edge of the main top portion 14, whereupon the top 14 may be permitted to drop or rest upon the partially withdrawn leaf 31.

Thereupon the extension leaf may be fully extended until the front edges of the stops 33 engage the rear side of member 10 to limit the further withdrawal of the leaf, whereupon, the edge of the main top will drop down

into position behind the inner edge of the leaf and rest upon the upper surface 34 of the slide rails 29. The upper surfaces of the extension or leaf members will 5 be protected against injury or scratching by the projecting lower edges of the longitudinal frame members 17^a, which extend below the lower edge of the inturned flange 15 of the top.

10 A similar method of withdrawing or extending the leaf 30 at the right hand side in the Figs. 3, 4 and 5 is carried out. The relative positions of the stops 32, 32, is such that the inner edges of the leaves 30 and 31 are so 15 spaced apart as to accommodate snugly, yet freely between them, the main table top 14. In such fully extended operative position the upper surface of the top 14 will occupy a horizontal plane coinciding with that of the 20 upper surfaces of the leaves 30 and 31.

It has proved very difficult in folding tables to arrange the various parts so that a drawer of any considerable size may be provided. According to my construction, with 25 the slide rails located widely apart and transversely of the frame, ample space is provided for the location of a drawer which pulls out from the center portion of the side frames. A drawer 36 is illustrated disposed in an 30 opening formed in one of the side frame members 10. Suitable slide rails 39 are secured in the proper position to the frame members 10 to slidably support the drawer.

In certain instances it has been found preferable to employ as the means for securing 35 the table top to the supporting top a pair of angle plates 40^x, as shown in Fig. 7. In such cases two plates 40 are employed and one leg 40 secured rigidly to the under side 40 of each end of the central bar 18 of the top frame 17, while the other depending leg 40 is provided with a longitudinal slot 42 to loosely receive a screw or bolt 43 which is 45 rigidly secured to the inner side of the end frame member 11 in order to accord a limited movement to said angle plate and the table top to which it is secured.

Having thus described my said invention, what I claim and desire to secure by Letters 50 Patent is:

1. An extension table comprising a frame, a main table top, a longitudinal member upon its under side dividing the same into two longitudinal recesses, securing means on said 55 longitudinal member and movably engaging said frame to permit of combined vertical and transverse tilting movements of said top, a pair of leaves normally housed wholly within the longitudinal recesses in the under- 60 side of said top, and means for slidably supporting said leaves upon said frame for movement thereof from inoperative to operative positions, and vice versa in a horizontal plane, substantially as specified.

2. An extension table combination com-

prising a frame, a table top formed with a dependent flange surrounding the same, a centrally disposed longitudinal bar carried by the lower side of said table top within said flange, a pair of cross rails carried by 70 said frame, a pair of leaves, slide rails carried by said leaves, interacting means associated with said cross rails and said slide rails for guiding said leaves in a horizontal plane, connecting means between said bar and said cross rails for permitting a predetermined tilting movement of said table top cooperative with the withdrawal of said leaves and their retraction below said top and within said flange, substantially as specified. 75

3. An extension table comprising a frame, a table top supported thereon and adapted for limited vertical movement relative to 80 said frame and tilttable towards each of two of its edges; said table top having its underside recessed, a pair of leaves normally lying wholly within the outlines of said top and mounted for movement in a horizontal plane outwardly of said recessed table top and inwardly into said recessed top, and means for guiding said leaves to projected and retracted positions, substantially as specified. 85

4. An extension table comprising a frame, a table top supported thereon and adapted for limited vertical movement relative to 90 said frame and tilttable towards each of two of its opposite edges; said table top having its underside recessed, a pair of leaves normally housed within said recessed portion, and movable in a horizontal plane outwardly of said table top and inwardly within the outline of said table top, and means for guiding said leaves in their movements to projected and retracted positions, substantially 95 as specified. 100

5. An extension table comprising a frame, a table top supported thereon having a recess in its under side, means yieldingly securing 105 said table top to said frame and permitting a limited vertical movement and the tilting of said table top towards each of two of its edges, a pair of leaves normally housed within the recess of said table top and movable in a horizontal plane outwardly of said table top to operative positions and inwardly into the recess of said table top to inoperative position, and means for guiding said leaves to 110 said operative and inoperative positions, substantially as specified. 115

6. An extension table comprising a frame including longitudinal and transverse members, a table top supported thereon having a recessed under side, a plurality of attaching 120 members secured to the under side of said table top and extending loosely through certain of said transverse frame members for permitting the tilting of said table top towards each of two of its opposite edges, a pair 125 of leaves normally housed within the recessed 130

under side of said table top and movable in a horizontal plane outwardly of said table top to operative position and inwardly into the recessed underside of said table top to inoperative position, and means for guiding said leaves to said operative and inoperative positions, substantially as specified.

7. An extension table comprising a table including longitudinal and transverse members, a table top supported thereon having a recessed under side, a plurality of bolts secured to the under side of said table top and extending loosely through certain of said transverse frame members for permitting the 10 tilting of said table top towards each of two of its opposite edges, a pair of leaves normally housed within the recessed under side of said table top and movable in a horizontal plane outwardly of said table top to operative position and inwardly into the recessed under side of said table top to inoperative position, and means for guiding said leaves to said operative and inoperative positions, substantially as specified.

8. An extension table comprising a frame including longitudinal and transverse members, a table top supported thereon having a recessed under side, a pair of angle plates secured to the underside of said table at opposite ends thereof, and each having a depending slotted portion provided with a slot, and securing means passing through said slot and into certain of said transverse frame members for permitting the tilting of said 20 table top towards each of two of its opposite edges, a pair of leaves normally housed within the recessed underside of said table top and movable outwardly of said table top to operative position and inwardly into the recessed 30 portion of said table top to inoperative position and means for guiding said leaves to said operative and inoperative positions, substantially as specified.

Signed at the city of New York, in the 40 borough of Queens, in the county of Queens, and State of New York, this 26th day of March, one thousand nine hundred and thirty.

LOUIS J. VIEHMANN.
